(57) **CLAIM**

The ornamental design for a holder for a battery-powered tool, as shown and described.

DESCRIPTION

This application may be related to subject matter disclosed in (i) U.S. non-provisional utility App. Ser. No. 16/986,235 entitled "Holder for a battery-powered tool" filed Aug. 5, 2020 in the name of Kenneth M. Wages (now Pat. No. 11,446,809), (ii) U.S. design App. Ser. No. 29/849,753 entitled "Holder for a battery-powered tool" filed Aug. 14, 2022 in the name of Kenneth M. Wages (now Design Pat. No. D. 1,002,321), and (iii) U.S. design App. Ser. No. 29/858,446 entitled "Holder for a battery-powered tool" filed Oct. 31, 2022; all three of said applications are incorporated herein by reference in their entireties.

FIG. 1 is a front view of a holder for a battery-powered tool showing my new design or a mirror image thereof;

FIG. 2 is a back view thereof;

FIG. 3 is a top view thereof;

FIG. 4 is a bottom view thereof;

FIG. 5 is a right side view thereof;

FIG. 6 is a left side view thereof;

FIG. 7 is a front, right, and top perspective view thereof;

FIG. 8 is a front, left, and top perspective view thereof;

FIG. 9 is a front, right, and bottom perspective view thereof;

FIG. 10 is a front, left, and bottom perspective view thereof;

FIG. 11 is a front view showing a state of use in a vertical orientation;

FIG. 12 is a front view showing a state of use in a horizontal orientation;

FIG. 13 is a right side view showing a state of use; and, FIG. 14 is a front, right, and top perspective view of FIG. 1, showing additional environment on the top surface.

The dash-dash broken lines shown in FIGS. 1-14 depict portions of the holder for a battery-powered tool holding tool that form no part of the claimed design. The dash-dash broken line shown in FIGS. 11-12 depict a battery powered tool and form no part of the claimed design. The dash-dash broken lines shown on the top surface of FIG. 14 depict environmental structure that forms no part of the claimed design.
